CONVERSION OF HYDROCARBON OILS

Bernard L. Kramer, Chicago, Ill., assignor to
Universal Oil Products Company, Chicago,
Ill., a corporation of Delaware

Application June 30, 1937, Serial No. 151,126

3 Claims. (Cl. 196—48)

This invention relates to processes for converting higher boiling hydrocarbon oils into lower boiling hydrocarbon oils and, more particularly, to a method and means of improving the thermal efficiency of modern cracking systems by a related and interdependent combination of heat exchange steps whereby what would otherwise be waste heat is transferred to various zones of the system wherein it may be advantageously utilized.

The invention is specifically directed to the general type of process known in the art as selective cracking and, more particularly, to a selective cracking system wherein reflux condensate formed by fractionation of the vaporous conversion products is separated into selected relatively low-boiling and high-boiling fractions which are cracked in separate heating coils under independently controlled temperature and pressure conditions.

In selective cracking systems of the type above mentioned, it has been found advantageous to remove a substantial quantity of heat from the conversion products after they have undergone the desired degree of cracking, whereby to control the cracking time and prevent excessive continued conversion which would result in the formation of excessive quantities of coke and/or fixed gases to the detriment of optimum yields of good quality gasoline and residual liquid. In the present invention this is accomplished by transferring excess heat from the hot conversion products to the cracking stock being supplied to the light oil heating coil of the system. By this method of operation, I not only accomplish the desired cooling of the hot conversion products and control of the cracking time but, in addition, by thus preheating the light oil cracking stock, I materially reduce the load imposed upon the light oil heating coil and furnace so as to conserve fuel and improve the thermal efficiency of the process and also increase the useful life of the high temperature cracking equipment.

As a further feature of the invention, which is cooperative with that above mentioned, I provide for preheating all or a portion of the fresh oil charging stock for the process by passing the same in indirect or direct heat exchange, or both, with the vaporous conversion products undergoing fractionation, whereby to improve the efficiency of the fractionating step and decrease the required size of the fractionating equipment and further improve the thermal efficiency of the process by transferring excess heat from

the vaporous conversion products to the charging stock and thereby decreasing the heat which must be imparted thereto for cracking in the heating coil or coils of the system.

The present invention does not reside in any particular single feature of the process herein described and illustrated but rather in the cooperative and interdependent combination of heat exchange steps whereby heat is transferred from certain zones of the system wherein it is not required or actually detrimental to other zones wherein it serves a useful and advantageous purpose.

One specific embodiment of the invention comprises heating an oil of relatively high-boiling characteristics to cracking temperature at superatmospheric pressure in a heating coil, simultaneously heating an oil of relatively low-boiling characteristics to an independently controlled higher cracking temperature at superatmospheric pressure in a separate heating coil, passing resulting heated products from both heating coils through substantially the entire length of an enlarged insulated reaction chamber, transferring both vaporous and liquid conversion products from said reaction chamber to a reduced pressure vaporizing and separating chamber wherein said liquid products are further vaporized, separating vapors and residual liquid conversion products in said vaporizing chamber and separately removing the same therefrom, subjecting said vapors to fractionation for the formation of reflux condensate, subjecting fractionated vapors of the desired end-boiling point to condensation, recovering the resulting distillate, and passing at least a portion of the fresh hydrocarbon oil charging stock for the process in indirect heat exchange with the vapors undergoing said fractionation, separating said reflux condensate into selected relatively low-boiling and high-boiling fractions, commingling the preheated charging stock with high-boiling fractions of the reflux condensate and supplying the commingled materials to the first mentioned heating coil, passing at least a portion of said selected low-boiling fractions of the reflux condensate first in indirect heat exchange with said vapors in the vaporizing and separating chamber, thence in indirect heat exchange with the hot conversion products in said reaction chamber at a point therein adjacent their point of removal from this zone and supplying the thus preheated low-boiling reflux condensate to the second mentioned heating coil.

The above mentioned and further objects and advantages of this invention and the manner of attaining them will be explained more fully in conjunction with the following description of the accompanying diagrammatic drawing, which illustrates one specific form of apparatus in which a process of the invention may be conducted.

Referring to the drawing, charging oil for the process is supplied through line 1 and valve 2 to pump 3 whereby it may be fed through line 4 and valve 5 and coil 6, which is disposed within fractionator 22. The charging stock is preheated in coil 6 by indirect heat exchange with the vapors undergoing fractionation in fractionator 22 and thence directed through line 7 and valve 8 into line 9, wherefrom it is supplied to heating coil 10. By this method a relatively cool charging oil is preheated before being supplied to the heating zone for conversion, and at the same time serves as a means of assisting cooling and fractionation of the vapors in fractionator 22. When desired a portion or all of the fresh charging oil may be supplied from line 4, through line 23 and valve 24 directly into the fractionator or preheated charging stock from coil 6 may be introduced into the fractionator from line 7 through line 25 and valve 26.

Heating coil 10 is located in furnace 11 of any suitable form by means of which the oil is heated to the desired cracking temperature, preferably at superatmospheric pressure, and the heated products are directed from the heating coil through line 12 and valve 13 into the upper portion of reaction chamber 14.

Chamber 14 is preferably insulated to conserve heat and preferably maintained at cracking temperature and superatmospheric pressure, whereby the heated products supplied thereto undergo further conversion in their descent through substantially the entire length of this zone, excessive cracking being prevented by partially cooling the products at a point adjacent their point of removal from the reaction chamber. This controlled cooling is accomplished by passing the conversion products in indirect heat exchange with low-boiling reflux condensate from fractionator 22, which low-boiling reflux condensate is passed through coil 50, as will be later described.

Vaporous and liquid conversion products are withdrawn in commingled state from the lower portion of reaction chamber 14 and directed through line 15 and valve 16 to vaporizing chamber 17. It is also within the scope of the invention to omit reaction chamber 14 from one or both cracking steps of the system, when desired, in which case the vaporous and liquid conversion products from one or both of the heating coils 10 and 44 may be supplied directly therefrom to separating chamber 17, by well known means, not shown.

Vaporizing and separating chamber 17 is preferably operated at a substantially reduced pressure relative to that utilized in reaction chamber 14, when the reaction chamber is employed, and, in any case chamber 17 is preferably operated at lower pressure than the heating coils. Separation of the heavy conversion products, which remain unvaporized in chamber 17, from the vaporous conversion products is accomplished in chamber 17. The vapors are partially cooled and the desired separation of heavy materials therefrom is assisted by passing the same in indirect heat exchange in chamber 17 with low-boiling reflux condensate from fractionator 22, said low-

boiling reflux condensate being passed, as will be later described, through coil 41 in the upper portion of chamber 17. When desired, any well known fractionating means such as perforated pans, bubble trays, packing or the like, not shown, may be provided in the upper portion of chamber 17 to assist in separation of the desired products therein. The residual liquid may be withdrawn from the lower portion of chamber 17 through line 18 and valve 19 or, when desired, may be reduced to substantially dry coke therein by any well known means, not illustrated. The vaporous conversion products are directed from the upper portion of chamber 17 through line 20 and valve 21 to fractionator 22.

The vaporous conversion products supplied to fractionator 22 are fractionated therein by any well known fractionating means, such as perforated pans, bubble trays, or the like, not shown, and the ascending vapors are cooled by indirect and/or direct heat exchange with charging stock supplied directly thereto and/or passed, as previously described, through coil 6. The heavier components of the vapors are thereby condensed as reflux condensate which is further treated within the system, as will be later described. Further cooling of the vapors to maintain the desired vapor outlet temperature from the fractionator may be accomplished, when required, by circulating any suitable cooling medium through coil 27, in the upper portion of the fractionator, or by the direct introduction of a suitable light cooling oil, by well known means, not shown.

The oils supplied to fractionator 22 are separated by fractionation therein into a vaporous product of the desired end-boiling point, a selected relatively low-boiling reflux condensate and a selected relatively high-boiling reflux condensate. The fractionated vapors are withdrawn from the upper portion of fractionator 22 through line 56 and valve 57 to condenser 58 wherefrom the resulting distillate and uncondensed gases pass through line 59 and valve 60 to collection and separation in receiver 61. Distillate is withdrawn from receiver 61 through line 64 and valve 65 to storage or to any desired further treatment and the uncondensed gases are released from the receiver through line 62 and valve 63.

The relatively high-boiling reflux condensate formed in fractionator 22 is withdrawn from the lower portion of this zone through line 30 and valve 31 to pump 32 whereby it is fed through line 33 and valve 34 into line 9 and thence to further cracking in heating coil 10 together with a portion or all of the preheated charging oil.

The relatively low-boiling reflux condensate formed in fractionator 22 is withdrawn from a suitable line 35 and valve 36 to pump 37 whereby it may be fed all or in part through line 38, line 39, valve 40 into and through closed coil 41, positioned in the upper portion of chamber 17, passing therefrom through line 42 and valve 43 into line 38, wherefrom it may be supplied to heating coil 44 through valve 55, valve 54 in line 38 being totally or partially closed.

Heating coil 44 is located in furnace 45, of any suitable form, by means of which oil is heated to the desired conversion temperature preferably at superatmospheric pressure and passed therefrom through line 46 and valve 47 to reaction chamber 14 or, when desired, it may be supplied directly from coil 44 to vaporizing chamber 17 by any well known means, not shown.

When desired, all or a portion of the high-boiling reflux condensate from fractionator 22

either with or without first passing through coil 41, may be directed through line 48, valve 49 into and through closed coil 50 positioned in the lower portion of reaction chamber 14, passing therefrom through line 51 and valve 56 into line 38 and thence to heating coil 44, valve 55 in line 38 being either totally or partially closed.

The heated conversion products entering reaction chamber 14 from heating coil 10 and heating coil 44 are cooled through indirect contact with the low-boiling reflux condensate introduced through coil 50, thereby preventing excessive continued cracking of these conversion products and substantially preventing the formation of coke therein as well as reducing the formation of gas and improving the yield of the desired final products. The combined vaporous and liquid conversion products are withdrawn from reaction chamber 14 and supplied to chamber 17 as previously described, wherein the ascending vapors are further cooled and fractionated by their indirect contact with low-boiling reflux condensate introduced through coil 41. Vaporous products are supplied from chamber 17 to fractionator 22, wherein they undergo cooling and fractionation as previously described.

Line 52 and valve 53 are provided for use particularly in starting up the process when it is desired to fill the equipment with oil and at any time during an emergency in operation when it is necessary to supply oil direct to heating coil in order to avoid excessive temperatures therein.

Temperature and pressure conditions in the heating coils and the various other portions of the equipment will vary depending upon the type of charging stock being processed and the desired results. The temperature employed in heating coil 10 as measured at the outlet thereof, may vary, for example, from 825 to 975° F., or thereabouts, with any desired superatmospheric pressure ranging, for example, from 100-500 pounds, or thereabouts, per square inch. The temperature employed in heating coil 44, as measured at the outlet thereof, may vary, for example, from 900-1050° F., or more, with any desired superatmospheric pressure which may range, for example, from 200-800 pounds, or thereabouts, per square inch. The pressure utilized in the reaction chamber, when such a zone is employed, may be substantially equalized with that employed in the communicating heating coil utilizing the lowest pressure. The separating chamber and succeeding fractionating, condensing and collecting portions of the system are preferably operated at reduced pressure relative to that employed in the reaction chamber or in the heating coils and may range from 150 pounds, or thereabouts, per square inch, superatmospheric, down to substantially atmospheric pressure.

As a specific example of one type of operation which may be conducted in accordance with the features of the present invention in an apparatus such as illustrated and above described; the charging oil for the system is a Mid-Continent topped crude of approximately 25° A. P. I. gravity and is supplied at a temperature of approximately 100° F. to coil 6 and preheated therein by indirect heat exchange with the vaporous conversion products undergoing fractionation, to approximately 250° F. It is then admixed with the relatively high-boiling reflux condensate which is withdrawn from the lower portion of fractionator 22 at a temperature of approximately 700° F. and the commingled oils supplied to heating coil 10 at a temperature of approximately 575° F. wherein

they are heated to a conversion temperature of approximately 925° F. at a superatmospheric pressure of about 300 pounds per square inch. A relatively low-boiling fraction of the reflux condensate is withdrawn from fractionator 22 at a temperature of approximately 500° F. and is heated in coil 41, positioned in the upper portion of vaporizing chamber 17 to approximately 650° F. and further heated in coil 50, positioned in the lower portion of reaction chamber 14, to approximately 760° F. and is thence supplied to heating coil 44 wherein it is heated to a conversion temperature of approximately 975° F. at a superatmospheric pressure of about 400 pounds per square inch and supplied therefrom to reaction chamber 14. Reaction chamber 14 is maintained at a superatmospheric pressure of approximately 250 pounds per square inch, which pressure is reduced to approximately 50 pounds per square inch in the separating chamber and is substantially equalized in the succeeding fractionating, condensing and collecting portions of the system. This operation will produce per barrel of charging stock, approximately 55% of good antiknock gasoline and about 38% of good quality liquid residue, the remainder being chargeable principally to uncondensable gas.

I claim as my invention:

1. In a process for the cracking of hydrocarbon oils wherein an oil of relatively high-boiling characteristics is heated to cracking temperature at superatmospheric pressure in a heating coil, an oil of relatively low-boiling characteristics simultaneously heated to an independently controlled higher cracking temperature at superatmospheric pressure in a separate heating coil, resulting heated products from both heating coils passed through substantially the entire length of an enlarged insulated reaction chamber, also maintained at superatmospheric pressure, wherein they are subjected to continued cracking, the resulting vaporous and liquid conversion products withdrawn from the reaction chamber and introduced into a reduced pressure vaporizing and separating chamber wherein vaporous and residual liquid conversion products are separated and wherefrom they are separately removed, said vaporous conversion products subjected to fractionation for the formation of relatively high-boiling and relatively low-boiling reflux condensates which are returned, respectively, to the first mentioned and second mentioned heating coils for further cracking, fractionated vapors of the desired end-boiling point subjected to condensation and the resulting distillate recovered, the improvement which comprises passing fresh charging oil for the process in indirect heat exchange with vaporous products undergoing said fractionation, commingling the thus preheated charging stock with said high-boiling reflux condensate, supplying the commingled materials to the first mentioned heating coil and passing said low-boiling reflux condensate, prior to its introduction into the second mentioned heating coil, first, in indirect heat exchange with the vaporous conversion products in said vaporizing chamber and then in indirect heat exchange with said vaporous and liquid conversion products prior to their introduction into said vaporizing and separating chamber.

2. In a process for the cracking of hydrocarbon oils wherein an oil of relatively high-boiling characteristics is heated to cracking temperature at superatmospheric pressure in a heating coil, an oil of relatively low-boiling characteristics

simultaneously heated to an independently controlled higher cracking temperature at superatmospheric pressure in a separate heating coil, resulting heated products from both heating coils 5 passed through substantially the entire length of an enlarged insulated reaction chamber, also maintained at superatmospheric pressure, wherein they are subjected to continued cracking, the resulting vaporous and liquid conversion 10 products withdrawn from the reaction chamber and introduced into a reduced pressure vaporizing and separating chamber wherein vaporous and residual liquid conversion products are separated and wherefrom they are separately removed, said vaporous conversion products 15 subjected to fractionation for the formation of relatively high-boiling and relatively low-boiling reflux condensates which are returned, respectively, to the first mentioned and second mentioned heating coils for further cracking, fractionated vapors of the desired end-boiling point subjected to condensation and the resulting distillate recovered, the improvement which comprises passing fresh charging oil for the process 20 in indirect heat exchange with vaporous products undergoing said fractionation, commingling the thus preheated charging stock with said high-boiling reflux condensate, supplying the commingled materials to the first mentioned heating 25

coil and passing said low-boiling reflux condensate, prior to its introduction into the second mentioned heating coil, first, in indirect heat exchange with the vaporous products in said vaporizing and separating chamber and then in 5 indirect heat exchange with the hot conversion products in the reaction chamber at a point in this zone relatively close to that of their removal therefrom.

3. A conversion process which comprises heating 10 hydrocarbon oil to cracking temperature under pressure in a heating coil and passing resultant vaporous and liquid conversion products downwardly through a vertical reaction chamber maintained under cracking conditions of temperature and pressure, removing the vaporous and liquid conversion products as a mixture from the lower portion of the chamber and separating the same into vapors and residue in a reduced pressure separating chamber, passing hydrocarbon oil 15 to be cracked in indirect heat exchange with the vapors in the upper portion of said separating chamber and then in indirect heat exchange with the vaporous and liquid conversion products in the lower portion of said reaction chamber, and supplying the thus preheated oil to said heating coil. 20 25
